E. A. FRARY

Des. 172,787

SHOE SOLE

Filed Feb. 17, 1954

UNITED STATES PATENT OFFICE

172,787

SHOE SOLE

Evan A. Frary, Marshfield, Wis., assignor of one-half to Lloyd L. Felker, Marshfield, Wis., and one-half to David E. Crooker, Ontonogan, Mich.

Application February 17, 1954, Serial No. 29,061

Term of patent 14 years

(Cl. D7—5)

To all whom it may concern:

Be it known that I, Evan A. Frary, a citizen of the United States, residing at Marshfield, Wisconsin, have invented a new, original, and ornamental Design for a Shoe Sole, of which the following is a specification, reference being had to the accompanying drawing, forming a part hereof.

In the drawing:

Fig. 1 is a plan view of the tread surface of a shoe sole, showing my new design; and
Fig. 2 is an edge view thereof.

I claim:

The ornamental design for a shoe sole, substantially as shown.
